UNITED STATES PATENT OFFICE

2,371,096

HOT-WATER HEATER

Cosmo D. Zipeto, Philadelphia, Pa.

Application February 3, 1944, Serial No. 520,927

2 Claims. (Cl. 122—356)

This invention relates to water heaters, and a principal object of the invention is to provide a heater of simple and inexpensive construction having exceptionally high operating efficiency.

In the attached drawing;

Fig. 1 is a vertical sectional view of a heater made in accordance with the invention;

Fig. 2 is a section on the line 2—2, Figure 1;

Fig. 3 is a detached view in perspective illustrating certain of the elements of the heater structure, and

Fig. 4 is a view in perspective of a fragmentary part of the heating coil.

With reference to the drawing, the heater in a preferred embodiment comprises a hollow base section 1 within which are installed the heating elements in the form, in the present instance, of two gas burners designated by the reference numeral 2. Each of these burners is connected through a pipe 3 with a gas source, not shown. Also mounted in the base section 1 is a tank 4 to which water is fed through a supply pipe 5, said tank having a drain pipe 6 which is normally closed by a valve 7. To the top of the tank is connected the lower end of a flat duct 8, made preferably of copper or other metal of high heat conductivity. The duct 8 extends upwardly from the tank 4 in serpentine formation, said pipe having in effect a plurality of substantially horizontal sections 9 superimposed in spaced relation one above another and connected in series with each other by way of curved sections 11. The upper end of the duct 8 is connected to the underside of a tank 12 from which a pipe 13 extends to a hot water reservoir, or to a heating system as the case may be.

The base section 1 is preferably in the form of a casting having a bottom flange 14, vertical side walls 15, and an upper outwardly extending flange 16 which terminates in an up-turned edge

11. The upper flange 16 with its up-turned edge forms a shallow receptacle for the base flange 18 of a superimposed section 19. This section, also in the form of a casting, is substantially the same as the base section 1 but is of somewhat lesser vertical height in the present instance. The upper flange 21 of the section 19 with its up-turned edge 22 forms in turn a hollow receptacle for the base flange 18 of a superimposed section identical in form to the section 19. These identical sections will be designated by the same reference numerals. It will be noted that the section 19 which adjoins the base section 1 is provided with openings 23 and 24 for passage of the pipes 5 and 6 respectively.

The several superimposed sections 19 form, in conjunction with the base section 1, a hollow shell or stack which embraces the serpentine duct 8, the stack being closed at the top by a cap section 25 which seats upon the upper section 19. The latter section supports the tank 12 and has in a wall thereof an opening 26 for passage of the pipe 13. With reference to Figure 2 it will be noted that the base section 1 has an opening 27 in one wall thereof through which draft air is admitted to the lower end of the stack, and to the burners 2 for combustion purposes; and the cap section 25 is provided with a port 28 from which a flue duct 29 extends to carry off the spent gases and products of combustion.

Between each of the sections 19 is a baffle 31, the form of which is best shown in Figure 3. The edge portions of each of these baffles seat in the shallow receptacle formed by the upper flange 21 of the associated section 19 and underlies the base flange 18 of the superimposed section. The baffle thus functions in part as a sealing gasket for the joints between the said sections. As shown in Figures 1 and 3 each of the baffles has at one end a recess 32 through which the duct 8 extends, these recesses also providing for passage upwardly through the stack of the hot gases from the burners 2. Each of the baffles 31 is provided with an end section 33 which closes the outer end of the recess 32 and completes the gasket function of the baffle. It will be apparent that with the aforescribed arrangement the hot gases from the burners 2 will be caused to pass upwardly through the stack in a tortuous path following the windings of the duct 8 and will thereby remain in intimate contact with the flat extended surfaces of the duct from the bottom to the top of the stack.

In assembling the heater structure described above, the base section 1 and the superimposed section 19 may be set up with the burners and the tank 4 in position, it being noted by reference to Figures 1 and 2 that the burners are supported upon cross bars 34, and the tank upon cross bars 35 secured in and extending across the base section. The lower end of the duct 8 may be attached to the tank 4 either before or after the latter has been mounted in the two lower sections of the stack as set forth and the duct, together with the upper tank 12, may be supported in the vertical position which it assumes within the assembly by suitable supporting means. Thereafter the lowermost baffle 31 may be placed

in position at the top of the first section 19 and the following section 19 then seated upon the baffle and within the up-turned edge 22 of flange 21 of the said first section. The sections may be secured together by bolts 36 or may be cemented together, as desired. The next higher baffle 31 is then placed in position, followed by the next higher section 19, and this operation is repeated until the stack has been built up to the required height. The cap section 25 is then mounted in the top section 19 to complete the stack structure. After the pipe and flue connections are made, the entire stack may be covered with the usual insulation in the form for example of the conventional asbestos cement, this outer insulating cover being indicated in the drawing by the reference numeral 37.

A heater constructed as described above exhibits an extraordinarily high efficiency, practically all of the sensible heat of the burning gases being utilized for heating the water which circulates through the system. Relatively cold water entering the tank 4 through the pipe 5 is subjected through the shell of the said tank to the effects of the direct flame of the burners 2, the heated water then passing upwardly through the duct 8 to the tank 12 from which it is distributed through the pipe 13. From the time that the water enters the tank 4 to the time it leaves the tank 12 it is subjected to the effects of the heated gases passing upwardly through the stack from the burners 2, the heated gases by reason of the baffles 31 following a tortuous course through the stack corresponding to the windings of the duct 8. It will be noted by reference to Figure 2 that the duct 8 is of substantial width and small depth, and the gases in passing upwardly act upon both faces of the duct and are thereby brought into effective heat exchange relation with substantially all of the water passing through the duct. Aside from the high operat-

ing efficiency, the heater is characterized by relative simplicity of form, it being noted that the sections 19 and the baffles 31-33 may be standardized for different sizes of heaters, and requiring for any given size but one form of casting and baffle aside from the base section 1 and the cap section 25.

While the invention has been described above in its application to water heaters, it will be understood that the apparatus may, as well, be used for generating steam. The term "water heater" as used above and in the appended claims is embracive of both of these uses.

I claim:

15. 1. In a water heater, a stack, a sinuate duct extending through the stack, said stack consisting of a plurality of hollow superimposed sections each having at the top a shallow peripheral receptacle for the base of the immediately superimposed section, baffles having their edge portions seated in the said receptacles of the respective sections and forming gaskets between said sections, said baffles extending between adjoining passes of the duct windings and forming a tortuous passage within the stack conforming to said windings, and means for passing heated gases and water through the said stack passage and the duct respectively.
20. 2. In a water heater, a stack, a sinuate duct extending through the stack, said stack consisting of a plurality of hollow superimposed sections, baffles having their edge portions confined and forming gaskets between said sections, said baffles extending between adjoining passes of the duct
25. 3. In a water heater, a stack, a sinuate duct extending through the stack, said stack consisting of a plurality of hollow superimposed sections, baffles having their edge portions seated in the said receptacles of the respective sections and forming gaskets between said sections, said baffles extending between adjoining passes of the duct windings and forming a tortuous passage within the stack conforming to said windings, and means for passing heated gases and water through the said stack passage and the duct respectively.
